US0D1078007S

(12) **United States Design Patent** (10) Patent No.: **US D1,078,007 S**
(45) Date of Patent: ** Jun. 3, 2025

(54) **FILTER HOUSING**

(71) Applicant: **Dometic Sweden AB**, Solna (SE)

(72) Inventors: **Samuele Meda**, Chichester (GB);
Rickard Hederstierna, Hägersten (SE);
Jason Svarc, Kinglake West (AU)

(73) Assignee: **Dometic Sweden AB**, Solna (SE)

(**) Term: **15 Years**

(21) Appl. No.: **29/840,307**

(22) Filed: **May 27, 2022**

(57) **CLAIM**

The ornamental design for a filter housing as shown and described.

DESCRIPTION

FIG. 1 is an upper perspective view of a filter housing, showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines depict portions of the filter housing that form no part of the claimed design.

1 Claim, 5 Drawing Sheets

See application file for complete search history.
